UNITED STATES PATENT OFFICE.

JOSEPH J. DOBES, OF CHICAGO, ILLINOIS.

HORN.

1,183,356.

Specification of Letters Patent.

Patented May 16, 1916.

Application filed February 2, 1914. Serial No. 815,903.

To all whom it may concern:

Be it known that I, JOSEPH J. DOBES, a citizen of the United States, and a resident of Chicago, in the county of Cook and 5 State of Illinois, have invented certain new and useful Improvements in Horns, of which the following is a specification.

The present invention relates more particularly to horns which may be secured to 10 the exhaust pipe of an internal combustion engine, such as is employed in automobiles, and has for its principal objects the provision of a horn or signal by which a plurality of harmonious, blending or chordant 15 tones may be produced, and which is of light weight, simple construction, strong and durable, of neat appearance and which will occupy comparatively small space when applied for use.

20 The combination of a plurality of resonant tubes grouped together and secured to a coupling member is well known in the art, and the present invention is directed more particularly to features of construction 25 whereby certain disadvantages in heretofore suggested structures arising from excessive weight, cost, multiplicity of parts, lack of rigidity of parts, size, necessities of repair, etc. are overcome.

30 In the accompanying drawings, which form a part of this specification, I have illustrated a preferred embodiment of these improvements, Figure 1 showing a face view or side elevation of the horn complete, 35 Fig. 2 being an end view of the horn complete looking directly toward the open end of the coupling, Fig. 3 being a transverse vertical section on the line 3—3 of Fig. 1, viewed in the direction of the arrows, and 40 Fig. 4 being a similar section on the line 4—4 of Fig. 1.

The horn proper includes a plurality of tubular resonators 10, 11, 12 and 13, their outer end preferably being closed, as by 45 the metallic disks 14. These resonators are preferably made of light brass tubing, and are of such length respectively as to produce tones which harmonize with each other when all are sounded at the same time; for 50 instance, the first, third, fifth and eighth of the musical octave may thus be produced. The relative length of the several tubes required to produce any desired chord is well known to those skilled in the art; but

the same may be determined by anyone by 55 reference to any elementary work on physics. At the coupling end of the resonators a portion of the tubing is preferably cut away, as at 15, providing an edge 16 which may be bent inward slightly if found desirable, as shown in Fig. 2, thus providing 60 a substantially straight edge adapted to break the current from the discharge ducts or nozzles and produce a tone. Such resonant tubes so cut away and indented are 65 well known.

The coupling 20 comprises preferably a hollow nut-like member 21 which may be internally threaded as at 22 (Fig. 2) whereby the horn may be attached to an exhaust pipe 70 or similar source of fluid pressure. The hollow interior of the coupling is defined in one direction by the wall 23, which is suitably apertured whereby fluid pressure may be discharged substantially against 75 the edges 16 of the respective horns. In the preferred construction I provide a plurality of discharge nozzles 24, consisting preferably of metallic tubing threaded, crimped or otherwise secured tightly in 80 the wall 23, and having their outer portions 24' flattened somewhat so as to reduce the pressure blast to the form of a flat and thin stream more suitable for contact with the edges 16 of the respective horns. The nozzles 85 24, 24' are so positioned that the gas or other pressure blast entering the hollow interior of the coupling will be discharged simultaneously against the edge 16 of each of the resonant tubes, thus producing the 90 desired chord or chime effect.

The coupling 20 is provided with resonator-tube holding means comprising preferably a plurality of integrally formed anchoring stops or projections 25 which extend outward from the coupling in the same general direction and are otherwise arranged substantially radially with respect to a central longitudinal line passing through the coupling, as is well shown in 100 the drawings, these projections 25 preferably having their side walls concave and so spaced from each other that the outer walls of the coupling ends of the tubular resonators and the substantially facing 105 curved walls of the projections substantially interfit, portions of the projections 25 preferably passing around the walls of the tubes

respectively to such an extent that the tubes respectively are tightly held between adjacent projections and prevented from moving in any direction at right angles to the longitudinal direction of the tubes. In other words, the resonant tubes are tightly locked between the outstanding projections 25 against all but twisting and longitudinal movement with respect to the coupling 20. 5 Preferably rivets 26 passing transversely through the projections 25 respectively and the walls of the tubes contiguous to each thereof secure the parts tightly and firmly together against all relative movement. By 10 these means a very strong and rigid connection is made, of very few parts, and which, owing to the coaction between the projections and the tubes, substantially defeats all tendency of the tubes to work loose. It 15 will be noted that the central portion of the completed structure is entirely free of tube-holding means, as is well shown in Fig. 4 wherein the reference character 23' denotes the outer surface of the wall 23 shown in 20 Fig. 2.

The resonant tubes may be held together more rigidly in their cluster-like arrangement by means illustrated wherein metallic clamping elements or brackets 30 are held 25 tightly upon adjacent tubes by bolts or rivets 31, each bolt or rivet also acting as a seat or spacing element for the tubes.

The coupling 20 with the projections 25 and also with suitable discharge nozzles if 30 desired integral therewith may be made by casting the same from iron or from any other suitable metal.

While I have illustrated and described a preferred construction of these improvements 35 it will be apparent to those skilled in the art that various changes may be made therefrom without departing from the spirit of this disclosure, and all such changes are 40

contemplated by me as fall within the scope of the appended claim.

45

I claim:

The combination of a plurality of cylindrical resonant tubes in a group side by side in substantially parallel relation and substantially equidistant from a central longitudinal line, a coupling for said tubes comprising a hollow nut-like portion having an integrally formed transverse wall at one end thereof, said wall being apertured for a discharge duct for each of said tubes, a discharge duct in each of said apertures and directed toward an edge in the wall of said tubes respectively, a plurality of projections integral with said nut-like portion substantially radially arranged in transverse view and extending longitudinally from said nut-like portion, each of said projections being concave longitudinally on opposite sides thereof whereby two such concave sides substantially face each other on adjacent of 60 said projections and form retaining walls respectively on substantially circular lines in transverse view, each of said resonant tubes being between two such retaining walls, said substantially facing retaining 70 walls respectively being relatively close together at the inner portions thereof whereby a firm seat is formed by said walls for said tubes respectively toward the central longitudinal line of said group, the outer portions 75 of said facing walls respectively being closer together than the diameter of the circle on which they are formed, and means for holding said tubes respectively against retraction longitudinally from their respective 80 retaining walls.

JOSEPH J. DOBES.
